HAND STRAP

Leverett M. Clark, Depew, N. Y., assignor to
 Waugh Equipment Company, Depew, N. Y., a
 corporation of Maine

Application July 7, 1932, Serial No. 621,259

6 Claims. (Cl. 105—354)

The invention relates to metallic hand straps as employed in passenger carrying vehicles for the convenience of standing passengers and has for its object to provide an improved form of hand strap of the general type shown in the patent to Doyle No. 989,237 and prior patents of the applicant Nos. 1,650,429 and 1,729,988, the object of the invention being to provide a novel form of connection between the tubular hand grip and the shank member or supporting arm that will preclude bending or rupturing the strap at the point of juncture between the hand grip and the supporting arm due to excessive pressure, in a lateral direction, being imposed on the strap by the user, when the strap has reached either end of its swinging movement and been arrested by the stop or stops provided for that purpose.

The invention is illustrated in the accompanying drawings, in which:—

Fig. 1 is a side elevation of the hand strap and its support partly broken away.

Fig. 2 is a side elevation of the complete strap.

Fig. 3 is a front elevation of the same.

Fig. 4 is an enlarged fragmentary side elevation, illustrating the details of the joint between the hand hold and the supporting arm or shank.

Figs. 5, 6 and 7 are views similar to those in Figs. 2, 3 and 4, illustrating a modified form of the connection.

As heretofore manufactured, hand straps of the character indicated have been formed with a generally stirrup-shaped hand hold or grip loop consisting of a porcelain-enamel tubular body portion having its two ends flattened and united to the flattened lateral faces of the arm or shank by screws or rivets. The hand straps thus constructed and assembled are usually mounted in passenger vehicles on horizontal supporting rails, or on individual brackets associated with stops and torsion springs that control and limit the swinging movement of the hand straps. When not in use, the straps are automatically moved to a position at an angle from the perpendicular and toward the side of the vehicle, so as to be out of the way of passengers. The stops permit the hand straps to be operated forward and backward throughout a definite range of swinging movement, as indicated in dotted lines in Fig. 1. When in either of these extreme positions, any attempt on the part of the passengers to force the straps beyond the normal limits of their movement, results in the imposition of heavy stresses tending to rupture the metal of the hand grip at the points of

juncture of the latter with the supporting arm or shank, which not infrequently produces breakage of the grip and more frequently breaks and impairs the enameled coating of the hand grip. This deformation of the strap and the chipping away of the porcelain-enamel are permanent impairments of the strap as a whole, producing unsightly appearance and destroying the orderly arrangement and disposition of the straps and, of course, when the hand hold or grip is broken at the point of juncture with the shank, it becomes necessary to replace the strap as an entirety. It is the purpose of the present invention to so secure the hand grip or loop member to the shank or supporting arm that the joint between the two will effectively resist any stresses tending to bend or distort the hand grip relatively to the shank or support.

Referring to Figs. 1 to 4, 1 indicates a typical shank or supporting member which is adapted to be connected for swinging movement to the usual rail or bracket and to be limited in its swinging movement by the usual stops, so that the strap, as a whole, cannot be moved beyond the positions indicated in dotted lines in Figs. 1 and 2. The lower end of the shank 1 is finished as a flat bar-like member 2 having parallel side faces which are provided near their lower ends with concave cavities 3, 3. The hand grip or loop 4 is of the usual construction comprising a body portion of enameled tubing bent to substantially stirrup form and having its ends flattened as at 5, 5 to engage the flattened lateral faces of the extension 2 of the shank, the said ends 5, 5 being secured to the extension 2 by means of rivets 6, 6. It will be particularly noted that the member 2 extends between and engages the terminal portions of the tubular body of the hand grip 4 with the heels or inner faces of the tubular ends snugly fitting the concave recesses 3.

By this construction of joint, it will be seen that bending moments applied to the strap as a whole, such as would be produced by the user forcing the shank against either of the stops, will be effectively resisted by the direct engagement of the terminal portions of the tubular member which have a large bearing surface in engagement with the interposed portion 2 of the shank and comparatively little of the lateral pressure will be transmitted to the thinner portions 5, 5 of the hand grip. It has been found that this particular construction of strap will withstand all ordinary stresses that can be imposed by the user without any bending or deformation of the

parts and without showing any tendency to crack or chip away the enamel of the hand grip.

The same general desirable effects are produced in the modifications shown in Figs. 5, 6 and 7, in which case the lower end of the shank or supporting arm 2 is flared outwardly and laterally in each direction to provide flat side faces engaged by the flattened ends 5' of the hand hold or grip 4, said ends being secured to the wedge-like extension 2' by the usual rivets 6. In this case, the wedge-like projection 2' is extended to engage the terminal portions of the tubular members of the grip 4, which terminal portions are finished with wing-like members 4' which merge into the flattened end sections 5' and afford an opening through which the lowermost rivet 6 may be passed. With this particular construction, a relatively large bearing area is provided between the lower portion of the wedge-shaped terminal 2' of the shank and the terminal portions of the tubular member 4, these bearing areas serving to take up any bending stresses and prevent the latter being transmitted to the relatively thin end sections 5' of the grip.

25 What I claim is:

1. A hand strap comprising a tubular hand grip loop having flat ends, and a rigid supporting arm having an end provided with flat sides secured to the flat ends of the grip by means of rivets and extending between and engaging the terminal portions of the tubular member, the lower end of the arm being provided with concave seats engaged by the terminal portions of the tubular member.

35 2. A hand strap comprising a tubular hand grip stirrup-like loop having sides diverging from their free ends toward the bight of the loop and having flattened ends, and a rigid supporting arm having an end provided with flat sides secured directly between the flattened ends of the loop and projecting beyond the flattened ends toward the bight of the loop, so as to underlie and engage against a part of the tubular portions of the loop sides.

40 45 3. A hand strap comprising a tubular hand grip stirrup-like loop having sides diverging from their free ends toward the bight of the loop and having flattened ends, a rigid supporting arm

having an end provided with flat sides secured directly between the flattened ends of the loop and projecting beyond the flattened ends toward the bight of the loop, so as to underlie and engage against a part of the tubular portions of the loop sides, and means on the arm cooperating with the end portions of the sides of the loop for maintaining said sides in said diverging relation.

4. A hand strap comprising a tubular hand grip stirrup-like loop having sides diverging from their free ends toward the bight of the loop and having flattened ends, a rigid supporting arm having an end provided with flat sides secured directly between the flattened ends of the loop and projecting beyond the flattened ends toward the bight of the loop, so as to underlie and engage against a part of the tubular portions of the loop sides, and means on the sides of the loop at the juncture thereof with said arm for resisting distortion of the loop with respect to the supporting arm in a direction normal to the plane of the loop.

5. A hand strap comprising a tubular hand grip stirrup-like loop having sides diverging from their free ends toward the bight of the loop and having flattened ends, and a rigid supporting arm having an end provided with flat sides secured directly between the flattened ends of the loop and projecting beyond the flattened ends toward the bight of the loop, so as to underlie and engage against a part of the tubular portions of the loop sides, the tubular end portions of the loop sides and said arm having portions engaging within one another for preventing distortion of the loop with respect to the arm.

6. A hand strap comprising a tubular hand grip stirrup-like loop having sides diverging from their free ends toward the bight of the loop and having flattened ends, and a rigid supporting arm having an end provided with flat sides secured directly between the flattened ends of the loop and projecting beyond the flattened ends toward the bight of the loop, so as to underlie and engage against a part of the tubular portions of the loop sides, the loop sides and said arm having interengaging projections and recesses.

LEVERETT M. CLARK.
